HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,273,958.

Specification of Letters Patent. Patented July 30, 1918.

Application filed January 26, 1916. Serial No. 74,460.

To all whom it may concern:

Be it known that I, HENRY G. VOIGHT, a citizen of the United States, residing in New Britain, in the county of Hartford and 5 State of Connecticut, have invented certain new and useful Improvements in Locks, of which the following is a full, clear, and exact description.

This invention relates to locks, and more 10 particularly to locks for the corridor doors of hotels. The invention is especially applicable to mortise locks having master keyed cylinders of such construction that when a bolt is protracted from the inside 15 of the room, it cannot be retracted from the outside of the room by the master key in the possession of the maid, although it can be retracted under these circumstances by the emergency key.

20 One of the primary objects of the invention is to furnish a very simple and efficient lock having these characteristics.

Another object of the invention is to provide a lock in which one of the keys acts as 25 a shut-out key so that after the bolt has been protracted thereby it cannot be retracted by the other keys, and in which this shut-out mechanism is very simple and effective.

30 A further object of the invention is to provide, in combination with a mortise lock mechanism having two different members, a master keyed cylinder lock which coöperates with these members in an improved 35 manner in the operation of the lock by the different keys.

To these and other ends, the invention consists in the novel features and combinations of parts to be hereinafter described 40 and claimed.

In the accompanying drawing,

Figure 1 is an elevation of a mortise lock embodying my improvements, showing the cover or cap plate removed, and the dead 45 bolt in the retracted position;

Fig. 2 is a view of the upper part of the lock, showing the dead bolt protracted by the thumb turn from the inside of the room;

Fig. 3 is a view similar to Fig. 2, showing 50 the bolt partly retracted by the emergency key from the outside;

Fig. 4 shows the position of the parts when the bolt is protracted from the outside by the guest key or master key;

55 Fig. 5 is a reverse view of the lock with

the dead bolt protracted from the inside of the room by the thumb turn;

Fig. 6 is a section on line 6—6 of Fig. 1; Fig. 7 is a section on line 7—7 of Fig. 2; Fig. 8 is a section on line 8—8 of Fig. 3; 60 Fig. 9 is a front view of the cylinder lock detached; and

Fig. 10 is a detail section on line 10—10 of Fig. 1.

I have shown my improvements as applied to a mortise lock having a single dead bolt which is protractable from the inside of the room by means of a thumb turn and from the outside of the room by means of a cylinder lock having a series of different 70 keys. The lock also has a knob controlled latch bolt. The particular features forming the subject of the present application may, however, be used to advantage in locks of widely different types. 75

In the particular form shown, the usual mortise lock case 20, having the face plate 21, is equipped with a dead bolt 22 operative from the outside of the room by means of a cylinder lock 23 having a series of keys, 80 said dead bolt being operative from the inside of the room by means of a thumb turn (not shown) engaging a thumb turn hub 24 of ordinary type. Beneath the dead bolt a latch bolt 25 is normally projected out of 85 the face plate by a spring 26, and is adapted to be retracted by knobs (not shown) connected in the usual way with a hub or rollback 27 actuating a yoke or knob shoe 28, which retracts the latch bolt in the customary manner by engaging a cross-head 29 on the latch bolt stem. 90

The dead bolt 22 has a shank 30 guided by a slot 31 on the fence or stump 32 cast on the back of the case, and the shank of 95 the dead bolt also has a slot 33 by means of which it clears the thumb turn hub 24. Above the slot 33, the bolt is provided with a pair of talons 34 adapted to be engaged by a cam arm, dog or rollback 35 on the 100 cylinder lock 23 previously mentioned. A primary tumbler 36 is bodily carried by the dead bolt being pivoted thereto at 37. This tumbler has a lug 38 adapted to coöperate in the usual manner with the fence or stump 32 on the case so as to lock the bolt either in the projected or retracted positions. At the rear extremity of the tumbler 36, the same is provided with a loop 39 which embraces and clears the thumb turn hub 24, and 110

on the upper part of the loop 39 is a projection 40 which lies between the talons 34, as shown in Fig. 5, and is adapted to be engaged by the rollback 35 of the cylinder lock for the purpose of releasing the lug 38 from the fence 32, while the rollback, in acting on the talons, projects or retracts the bolt.

Mounted below the dead bolt 22 is a slide 41 which is suitably guided for reciprocation in a line parallel to the dead bolt, and is adapted to protract the dead bolt through the actuation of the thumb turn hub 24. In the form shown, the slide 41 has a groove 15 engaging a guide fin 42 on the back of the case (Fig. 5), and a shoulder 43 projecting upwardly from the slide engages a recess 44 in the lower edge of the dead bolt. When the parts occupy the position shown in Fig. 20 1, the shoulder 43 engages the forward edge of recess 44 so that the dead bolt may be protracted by the forward movement of the slide, as shown in Fig. 5. The slide carries a post 45, on which is mounted a secondary 25 tumbler 46. This secondary tumbler 46 is adapted to be actuated either by the thumb turn hub 24 or by the rollback 35 of the cylinder lock. For this purpose, the secondary tumbler is provided with a pin 47 30 projecting over the loop 39 of the primary tumbler and located between wings 24^a, 24^b on the hub 24, while an arm 46^a at the free extremity of the secondary tumbler extends upwardly across the loop 39 and carries a 35 sweep 46^b lying alongside the upper part of the loop and the projection 40 thereof and alongside the talons 34 of the dead bolt. Under normal conditions, the sweep 46^a of the secondary tumbler overlies the talons of 40 the bolt in the manner shown in Fig. 1, it being understood that the projection 40 on the primary tumbler is located between the talons in a plane offset from the sweep 46^a. The secondary tumbler 46 co-operates with 45 a fence or stump 46^c on the back of the lock case, which is adapted to hold said tumbler and thereby the connected slide 41 either in the retracted position, shown in Fig. 1, or in the advanced position shown in Fig. 2. 50 A lug 48 on the intermediate portion of the secondary tumbler is located above a hook 49 depending from the primary tumbler, the arrangement being such that the depression of the secondary tumbler either through the thumb turn hub or through the cylinder lock mechanism will cause a corresponding depression of the primary tumbler, so as to disengage the same from the fence or stump 32.

Referring now to the detailed construction 60 of the cylinder lock 23, it will be observed that this cylinder lock has the usual case 50, face plate or escutcheon 51, and key plug or barrel 52. The dog or rollback 35 previously mentioned is secured on the rear end 65 of the key plug 52. Preferably, it embraces

an extension 52^a on the rear end of the key plug and is secured to said plug by means of screws 53. Surrounding the key plug is a sleeve 54 rotatable concentrically with respect to said key plug. Sectional pin tumblers 55 of the usual type connect the key plug, sleeve and casing, the arrangement being such that one key is adapted to rotate the key plug individually, while another key rotates both the key plug and sleeve, as hereinafter described.

In accordance with the present invention, the tumblers 36, 46 of the bolt are arranged to be operated jointly and simultaneously by the single rollback 35, in case one key is used, and when another key is used the rollback 35 will operate the tumbler 36 without operating the secondary tumbler 46. In other words, when the guest key or change key 56 is used to actuate the cylinder lock, the rollback 35 will be so rotated that its operating projection 35^a will turn in the plane of the primary tumbler 36, and out of the plane of the secondary tumbler 46, so that the tumbler 36 will be actuated individually, while when the emergency key 57, shown in Fig. 8, is used to actuate the cylinder lock, the operating projection 35^a of the rollback will be rotated in the plane of the secondary tumbler so as to actuate 95 said secondary tumbler and thereby actuate the primary tumbler through the connection which exists between the hook 49 and lug 48 previously described. To accomplish these results, one of the rotary tumbler controlled members of the cylinder lock is displaceable rearwardly when the tumblers have been racked in a predetermined manner by one of the keys, whereas said member is not displaceable rearwardly when another 100 key is used. In the particular example illustrated, the sleeve 54 is movable endwise of the casing 50 when the emergency key is used, and to permit this the shoulder 58 at the forward end of the sleeve operates in a somewhat wider rabbet 59 in the face plate of the cylinder, so that when the sleeve is released and turned by a key, as shown in Fig. 8, the sleeve may move rearwardly until the shoulder 58 takes up against a shoulder 60 110 on the casing of the cylinder. In other words, the shouldered portion of the casing at the face of the cylinder which limits the endwise movement of the sleeve is farther back than in ordinary cylinders so that the sleeve may have an appreciable rearward movement. In this operation, the sleeve is locked by the pin tumblers to the key plug so that the latter is likewise carried rearwardly together with the rollback 35 so that 115 instead of rotating in the normal plane of rotation, to wit, the plane of the primary tumbler, the rollback is carried rearwardly and rotated in the plane of the secondary tumbler. Before the sleeve is turned on its 120

axis, it should be held against rearward movement by suitable means, which relieves the pin tumblers of strain. To this end, I may attach to the rear of the cylinder lock 5 a plate 61 which is secured to the upper portion of the cylinder by screws 62 (Fig. 10), and has a depending tongue or lip 63 abutting against the rear face of a cam member 64 screwed or otherwise secured to the rear 10 extremity of the sleeve 52. When the emergency key 57 is inserted into the cylinder, the engagement between the lip 63 and the cam 64 will take up rearward thrust on the sleeve, and thereby relieve the tumblers of 15 strain and wear, but when the sleeve is turned by the emergency key 57, the cam 64 will disengage the lip 63 and thereby permit the sleeve to be thrust rearwardly under the usual pressure on the key so that the roll- 20 back 35 will be rearwardly displaced, as above explained. By preference, the cam 64 embraces the rear extremity of the key plug and is screwed against the rear face of the sleeve, that part of the cam engaging the 25 lip 63 being in the form of a radial projection which is rounded off at its rear face, as shown at Fig. 10, while the coöperating lip 63 is rounded off at the front face thereof. In Fig. 6, I have shown the position of the 30 parts when the change key 56 is inserted into the cylinder. This change key racks the pin tumblers in such a manner as to release the key plug for independent rotation, while the sleeve 54 remains locked to the casing of 35 the cylinder. By using this change key, the tumbler 36 may be actuated individually and the dead bolt may be protracted independently of the slide 41, as shown in Fig. 4. As the primary tumbler is depressed, the hook 40 49 thereon is moved out of engagement with the lug on the secondary tumbler, so that the bolt and the primary tumbler move together, while the slide 41 and the secondary tumbler remain stationary. When the emer- 45 gency key is inserted into the cylinder, the pin tumblers are racked so as to permit the key plug and sleeve to rotate together. When the key is inserted so as to release the sleeve and key plug from the casing, 50 rearward movement of the rollback 35 is at first prevented by the engagement of lip 63 with cam 64, as previously explained, but when the key is turned in either direction, the projection of the cam 64 passes clear of 55 the lip 63, and is then immediately moved rearwardly by the usual pressure of the hand of the person actuating the lock so as to carry the rollback 35 into the plane of the secondary tumbler, as hereinbefore de- 60 scribed. If, however, the pressure on the key is not sufficient to move the rollback to its rearmost position, this will be effected by the cam action of the cam 64 on the casing of the cylinder lock, which is cut away to 65 present cam surfaces 65 adapted to be con- tacted by the cam 64, as the latter is rotated in one or the other direction and to force the rollback 35 in a rearward direction. The cam 64 rotates in contact with the rear face of the cylinder casing after said cam 70 has been thrust rearwardly by one of the cam surfaces 65 or by the pressure of the hand on the key, and therefore it will be understood that the cam or key thrusts back the rollback 35 when said key has been 75 turned to a very slight extent indeed, and that thereafter the rollback is prevented from moving out of the plane of the secondary tumbler until the key is rotated through nearly three hundred and sixty de- 80 grees, or is turned back to the initial position. As the parts approach their initial position, the cam 64 strikes against the lip 63, which is also in the nature of a cam, and said lip forces the cam forwardly again so 85 that when the tumblers are lined up for the removal of the key the sleeve, key plug and rollback will occupy the normal positions relatively to the cylinder.

Supposing that the improved lock is used 90 on the door of a hotel room, the thumb turn is turned by the guest from the inside of the room, when it is desired to lock the door against intrusion. In this operation, the hub 24 depresses the secondary tumbler (releasing it from fence 46^c), which tumbler in turn depresses the primary tumbler through the connection 48, 49, and then when the primary tumbler has been pulled out of engagement with the fence 32, the continued 95 rotation of the hub 24 will push the secondary tumbler forwardly. This secondary tumbler in turn carries forward the slide 41 which, by the engagement of shoulder 43 with the lower portion of the dead bolt, 100 protracts the dead bolt concurrently with the slide, as shown in Fig. 5. In the protracted position, the bolt is deadlocked by the fence 32 coöperating with the primary tumbler and by the slide, which in turn is 105 deadlocked in the advanced position by the fence 46^c coöperating with the secondary tumbler. I have not shown the maid's key, nor the grand-master key, but it will be 110 understood that under the conditions noted, these keys will be inoperative to retract the dead bolt, for the reason that said keys, like the guest key 56, rotate the key plug of the cylinder individually and therefore do not carry the rollback 35 back into the plane 115 of the secondary tumbler. Supposing that the maid inserts her key, the rollback 35 will rotate in the normal plane and will be inoperative because it will clear the secondary or emergency tumbler 46, as indicated in 120 Fig. 2. The door can still be opened by the emergency key, however, which thrusts the rollback 35 rearwardly into the plane of the secondary tumbler and actuates the primary tumbler concurrently with the secondary 125 130

tumbler to release the bolt, after which the rollback engages the talons to retract the bolt.

The emergency key will also act as a shut-out key for locking the door in such a manner that it cannot be opened by the other keys of the series. In protracting the bolt, the emergency key causes the rollback 35 to actuate the secondary tumbler and this secondary tumbler in turn actuates the primary tumbler, so that in the protraction of the bolt both tumblers are operated in substantially the same manner in which they are operated by the thumb turn. In other words, when the bolt is protracted by the emergency key, the tumbler mechanism takes the position shown in Fig. 2. It has been previously explained that when the tumbler mechanism is in this position, the bolt cannot be retracted by the guest key, the maid's key, or any other key which is incapable of thrusting the rollback 35 rearwardly into co-operation with the secondary tumbler. In order to retract the bolt, the slide 41 must be moved back out of its forward position, shown in Fig. 5, and to do this the secondary tumbler which is carried by said slide must be released from the stump or fence 46. In other words, when the bolt and slide are projected together by the thumb turn or by the emergency key, it is impossible to retract the bolt by a key which does not actuate the secondary tumbler to release the slide.

It is important to note that the rollback 35 of the cylinder lock will give the primary tumbler a full depression, through the secondary tumbler, without the actual necessity of directly engaging the primary tumbler, because the rollback rotates on the same axis under all conditions (owing to the fact that the sleeve and key plug are concentric) and therefore the secondary tumbler is depressed to a sufficient extent to carry the primary tumbler out of locking engagement with its stump or fence. I do not limit myself, however, in all aspects of the invention to a construction in which a concentric key plug and sleeve are employed, nor to one in which the cylinder lock carries a single rollback, although in certain phases of the invention these features are of advantage. Neither do I limit myself in all aspects of the invention to a lock construction involving a dead bolt with primary and secondary tumblers. Various changes in the details may be made without departing from the scope of the invention as defined in the claims.

I do not claim herein certain features of my cylinder lock mechanism *per se* as claimed in my application Serial No. 74,461, filed of even date herewith.

What I claim is:—

1. In a lock, a dead bolt, a slide, a common tumbler mechanism for said dead bolt

and slide, and a cylinder lock having a 65 single cam or rollback movable bodily relatively to said lock for protracting the bolt with or independently of the slide; substantially as described.

2. In a lock, a dead bolt, a slide, interengaging tumblers mounted on the dead bolt and slide respectively, a cylinder lock, and a rollback carried by said cylinder lock and movable bodily relatively to said tumblers for engaging and operating either of said 75 tumblers; substantially as described.

3. In a lock, a dead bolt, a slide, a tumbler carried by the dead bolt, a tumbler carried by the slide, means of engagement between said tumblers, a cylinder lock, a rollback on 80 said cylinder lock, a key for moving said rollback into operating engagement with one of said tumblers, and another key for moving said rollback axially into operating engagement with the other tumbler; substantially 85 as described.

4. In a lock, a dead bolt, a slide movable parallel to said dead bolt, a thumb turn member to protract said dead bolt by means of said slide, and a cylinder lock having a 90 single rollback movable bodily to operate said dead bolt with or independently of said slide; substantially as described.

5. In a lock, a dead bolt, a slide, manually operable means at the inside of the door to 95 protract said bolt by means of said slide, a cylinder lock at the outside of the door, a rollback for said cylinder lock, a key to move said rollback into co-operation with both said bolt and said slide to protract the 100 bolt by means of said slide, and another key for operating said bolt independently of the slide by means of the same rollback, said cylinder lock being constructed to move said rollback bodily when operated by one of 105 said keys, substantially as described.

6. In a lock, a dead bolt, a slide movable parallel to said bolt, a common tumbler mechanism for said slide and said bolt involving two tumblers located in different 110 planes, means to operate said tumblers from the inside of the door, a cylinder lock at the outside of the door, a single rollback for said cylinder lock, a key for moving said rollback into co-operation with one of said tumblers to protract the bolt by means of the slide, and another key to protract said bolt independently of the slide by moving said rollback into engagement with the other tumbler, said cylinder lock being constructed 115 to move said rollback bodily when operated by one of said keys, substantially as described.

7. The combination with a mortise lock mechanism having two members lying in 125 different planes, and means for operating one of said members through the other, of a cylinder lock having a single rollback, a key

for moving said rollback into engagement with one of said members to actuate it independently, and another key for shifting said rollback into another plane of rotation to 5 actuate said last-named member through the other member; substantially as described.

8. The combination with a mortise lock mechanism having two members lying in different planes, and means for operating 10 one of said members by means of the other, of a cylinder lock, a single rollback for said cylinder lock, a key for rotating said rollback into engagement with one of said members to actuate it independently, and another 15 key for displacing said rollback rearwardly and rotating it into engagement with the other member so as to actuate said independently operable member through such other member; substantially as described.

20 9. The combination with a mortise lock mechanism having two members lying in different planes, and means for operating one of said members by means of the other, of a cylinder lock, a single rollback for said 25 cylinder lock, a key for rotating said rollback into engagement with one of said members to actuate it individually, and another key for displacing said rollback rearwardly and rotating it into engagement with the 30 other member so as to actuate said independently operable member through such other member, said rollback rotatable on the same axis by both of said keys; substantially as described.

35 10. The combination with lock mechanism having a primary tumbler and a secondary tumbler operating in different planes, and means for operating the primary tumbler through the secondary tumbler, of a cylinder lock, a rollback carried by said cylinder lock, a key for rotating said rollback into operating engagement with said primary tumbler in order to actuate the latter independently, and another key for moving 40 said rollback into the plane of said secondary tumbler and rotating said rollback into engagement with said secondary tumbler to actuate both tumblers; substantially as described.

45 50 11. The combination with mortise lock mechanism having primary and secondary members operating in different planes, of a cylinder lock having a rearwardly displaceable rollback adapted to engage and operate either of said members; substantially as described.

55 60 12. In combination with mortise lock mechanism having primary and secondary members lying in different planes, a cylinder lock, a rollback carried by said cylinder lock, a key for rotating said rollback in its normal plane into operating engagement with one of said members, and another key for displacing said rollback rearwardly with

respect to said cylinder lock and moving it 65 into operating engagement with said other member; substantially as described.

13. In combination with mortise lock mechanism having primary and secondary members lying in different planes, a cylinder lock, a rollback carried by said cylinder lock, a key for rotating said rollback in its normal plane into operating engagement with one of said members, and another key for displacing said rollback rearwardly with 70 respect to said cylinder lock and moving it 75 into operating engagement with said other member, said rollback rotatable about the same axis by both of said keys; substantially as described.

80 14. The combination with a cylinder lock having a casing and a concentric key plug and sleeve, of a rollback carried by the key plug, a mortise lock mechanism having two members operating in different planes, a key for rotating said rollback into operating engagement with one of said members, and another key for displacing said rollback rearwardly and rotating it in operating engagement with the other member; substantially as described.

85 15. In a lock, a dead bolt, a slide, a common tumbler mechanism for said dead bolt and said slide, and a cylinder lock having a cam or rollback movable in one plane for 90 protracting the bolt with the slide and movable in another plane for protracting the bolt independently of the slide; substantially as described.

95 16. In a lock, the combination of a bolt 100 mechanism having two tumblers lying in different planes, and a cylinder lock having a rollback movable axially to engage and operate either of said tumblers; substantially as described.

105 17. The combination of a pin tumbler lock having a key plug, a rollback fixed on the key plug, two keys, means for displacing said rollback in a rearward direction by one of said keys without so displacing it by the other key, 110 and mortise lock mechanism to coöperate with said rollback when the latter occupies either of two positions; substantially as described.

115 18. A cylinder lock having a rollback, a key for rotating said rollback in one plane, another key for rotating said rollback, a cam for thrusting said rollback into another plane as it is rotated by said second key, and a mortise lock mechanism having members arranged to be engaged and operated by said rollback when it lies in said respective planes; substantially as described.

120 125 19. A cylinder lock having a rollback, a key for rotating said rollback in a predetermined plane, a second key for commencing the rotation of said rollback in said plane and then thrusting the rollback into another

plane at a definite point in the rotation thereof, and a mortise lock having operating members lying in the respective planes, both arranged to be engaged and operated by said rollback; substantially as described.

20. A cylinder lock having a key plug, a sleeve surrounding the key plug, pin tumblers, a key for rotating the sleeve with the key plug, means for shifting the sleeve and key plug in an endwise direction when the sleeve is released by said second key, a rollback fixed to the rear end of the key plug, and a mortise lock mechanism constructed and arranged to be actuated by said rollback through either of said keys; substantially as described.

21. In a lock, a dead bolt, a slide, a common tumbler mechanism for said dead bolt and slide, and a cylinder lock having a cam 20 or rollback with a single operating projection for protracting the bolt with or independently of the slide.

22. In a lock, a dead bolt, a slide, inter-engaging tumblers mounted on the dead bolt 25 and slide respectively, a cylinder lock, and a rollback on said cylinder lock having a single operating projection for engaging and operating either of said tumblers.

23. In a lock, a dead bolt, a slide, a tumbler carried by the dead bolt, a tumbler carried by the slide, means of engagement between said tumblers, a cylinder lock, a rollback on said cylinder lock having a single operating projection, a key for moving said 35 operating projection into operative engagement with one of said tumblers, and another key for moving said operating projection into operative engagement with the other tumbler.

40 24. In a lock, a dead bolt, a slide, inter-engaging tumblers mounted on the dead bolt and the slide respectively, a cylinder lock,

and a rollback on said cylinder lock having a radial arm for engaging and operating either of said tumblers.

25. The combination with a mortise lock mechanism having two members lying in different planes, of a cylinder lock, a rollback on said cylinder lock having a single operating projection, a key for moving said operating projection into engagement with one of said members to actuate the same, and another key for moving said operating projection into engagement with the other member to actuate the same.

50 26. The combination with a mortise lock mechanism, having two members lying in different planes, of a cylinder lock, and a rollback on said cylinder lock having a radial arm constructed to engage and operate either of said members.

55 27. In a lock, a sliding bolt, means for operating said bolt including primary and secondary members operating in different planes, and a cylinder lock having a rollback with a single operating projection adapted to engage and operate either of said members.

60 28. In a lock, a sliding bolt, means for operating said bolt, comprising members positioned to operate in different planes, and a cylinder lock having a rollback with a single operating projection adapted to engage and operate any one of said members.

65 29. In a lock, the combination of a bolt, a pair of swinging members for operating said bolt positioned to swing in different planes, and a cylinder lock having a rollback with a single operating projection adapted to engage and operate either of said members.

In witness whereof I have hereunto set my hand on the 24th day of January, 1916.

HENRY G. VOIGHT.
